ROOFING SHINGLE

Gerald B. Payne, Scranton, Pa., assignor to The Patent and Licensing Corporation, Boston, Mass., a corporation of Massachusetts

Application January 9, 1931, Serial No. 507,605

8 Claims. (Cl. 108—7.5)

This invention relates to covering a structure such as a roof with so-called composition shingles that consist of a felted fabric saturated or impregnated with a waterproofing compound, such as asphalt or similar bitumen and coated on one or both sides with a high melting point blown asphalt in which is partially embedded a surfacing layer of granules such as crushed slate, tile or the like.

10 An object of my invention is to provide a set of complementary shingles of simple construction which can be laid with ease and rapidity by an unskilled workman.

Another object of my invention is to provide a set of shingles which have interlocking portions so positioned that when the shingles are laid, the butt ends of the individual shingles form a continuous straight line to present a pleasing appearance.

20 A still further object of my invention is to provide a set of shingles, which can be laid with a minimum amount of material to cover a given area consistent with adequate protection, which are so proportioned as to require a relatively small number of shingles to cover a unit area. Other advantages will be apparent from the following description and drawing in which;

Figure 1 represents a plan view of one of the shingles of the set,

30 Figure 2 represents a plan view of the other shingle of the set,

Figure 3 represents a plan view showing the appearance of several courses of shingles, shown in Figures 1 and 2, when laid.

35 Figure 4 represents the manner in which the shingles may be cut out from a web or sheet of well-known form of prepared asphalt coated and mineral surfaced roofing material.

According to the invention the shingle A is 40 of generally rectangular shape with butt and head edges 16 and 17, respectively, and equi-length parallel lateral edges 14 and 15, and with its major axis extending in the same direction as the butt and head edges thereof. On each of the 45 lateral edges 14 and 15 is a V shaped projection 18 that is spaced from the upper edge 17 a distance equal to the desired overlap between shingles of successive courses. Each of the lower corners of the shingle A is cut away in the form of a substantially right angle notch 11 to provide side tabs 19 and material for the tabs of the complementary shingle B hereinafter fully described. Each notch 11 is defined by the edges 12 and 13, with the lateral edge 13 extending parallel to the 55 head and butt edges and inwardly from the side

edges 14 and 15 a distance corresponding to the amount of overlap desired between the adjacent shingles in each course. The lateral edges 12 are parallel to the side edges 14 and 15 and extend inwardly from the butt edge 16 a distance 60 approximately one-half the length of the edge 13. The apex of each notch is preferably cut away by a small arcuate cut-out 45 that assists in applying the shingle and prevents tearing during the application thereof. The upper face of the shingle A has aligning means thereon which as shown consists of short slits 10 extending through the upper edge 19 and each of said slits being located a predetermined distance from its adjacent side 14 or 15.

70 The shingle B is complementary to shingle A and is also of a general rectangular shape with butt and head edges 26 and 27 respectively, and parallel lateral edges 24 and 25 equal in length to lateral edges 14 and 15 of shingle A, and with 75 its major axis extending in the same direction as the butt and head edges. Spaced from the upper edge 27 and located on the lateral edges 24 and 25 are V shaped notches 28 that are the counterparts of the projections 18 on the shingle A. 80 These notches serve as indicating means for the accurate desired vertical spacing of successive courses, and permit the applicator to properly position the shingle of each course in the horizontal direction by placing the butt edge of each 85 shingle in registry with the apex of a notch in a shingle of the immediately preceding course. On each of the lower corners of the shingle B, there is an outwardly extending side tab 21 complementary in shape to the notches 11 of shingle 90 A, and having at its upper corner an arcuate projection 54 which is the exact counterpart of the arcuate cut-out 45 on shingle A. The tab 21 has an upper edge 23 that is parallel to the butt and head edges 26 and 27 and of a length equal to 95 that of the upper edge 13 of the notch 11 of the shingle A, and a lateral edge 22 that is parallel to the lateral edges 24 and 25 and of a length equal to that of the lateral edge 12 of the notch 11 of the shingle A.

100 Shingle elements as thus described may be cut from a sheet of mineral surfaced roofing material without any waste as shown in Figure 4, where it is seen that the cutting operation may be performed by severing the sheet along spaced parallel transverse lines 60, 61 and 63 and along longitudinal line 62, connecting adjacent lines of severance 60 and 61. As will be noted the successive cuts 61 are disposed on alternately opposite sides of the successive cuts 60, and thus there 110

is formed a series of alternately occurring shingles A and B. At the junctures of each slit 61 with a slit 62, the sheet is cut along a small arc to define the cut-out 45 of shingle A and corresponding projection 54 of shingle B. The short slits 63 are in line with the cuts 61 and extend a slight distance inwardly from the head portion of each shingle. It will be understood of course that a sheet of any desired width, which is a multiple of 10 the height of the shingles to be produced may be employed, and a number of longitudinally extending rows of shingles may be cut with each row consisting of alternately occurring shingles A and B as already described, and the sheet being 15 slit longitudinally to separate the shingles of adjoining rows.

The shingles may be packed alternately, in the direction in which they are delivered, thus requiring a minimum amount of handling at this 20 point, and affording an adequate protection for the shingles in the bundle.

In laying the shingles and assuming for purposes of description that they are being laid from left to right, the left hand tab of a shingle B is 25 cut off to provide a straight edge which can be arranged in the usual way to coincide with the verge line of the roof. The shingle is then placed on the supporting structure and nailed at its upper left hand corner and at the approximate 30 center of the right tab 21. A shingle A is then taken from the bundle in which the shingles A and B are stacked alternately as heretofore described, and its left hand tab 19 is slid under the right hand side of the shingle B, the top corner 35 of which is free, until the cut-out 45 is in contact with the apex formed by the edges 23 and 25 of shingle B. In order that the shingles may simulate rectangular areas, with the butt edges extending in a continuous straight line, the shingle 40 A is swung about the contacting means until the upper edges 17 and 27 of A and B respectively, or the slit 10 and the edge 24 of A and B respectively, are in the same straight line, thus causing the lateral edge 25 of shingle B to be in the same 45 straight line with the lateral edge 12 of the notch in shingle A. A nail is then driven through the upper right hand corner of shingle B at 30 to pass through the upper left hand corner of shingle A and into the supporting structure. The 50 shingle A is further nailed at 31 at the diagonally opposite lower corner adjacent the lateral edge 15. The left hand tab 21 of another shingle B, which is the next shingle in the bundle, is slid under the lower right hand free corner of the shingle A until the apex formed by the upper 55 edge 23 of the tab at the lower left-hand corner of the shingle B is in contact with the circular cut-out 45 in the notch 11 of shingle A. Shingle B is swung about this line until the upper edges 60 17 of shingle A and 27 of shingle B are in the same straight line. A nail is then driven at 32 in the upper left hand corner of the shingle B and passes through the upper right hand corner of the shingle A and into the supporting structure. This shingle is further fastened by projecting a nail through the approximate center of the tab 21 at the lower right hand corner of this shingle. This is continued until the course is completed.

76 The next course is laid by cutting a shingle, either A or B, so that its exposed lateral right hand edge will be substantially coincident with the center line of the first laid course. The shingle B, for example, is laid so that the exposed 75 edge is at the center of the strip B in the preced-

ing course and so that the butt edge of the strip is in alignment with the notch 23 of the lower strip, with the head and side laps equal. Nails are driven through the upper left hand corner of this strip B and through the right tab 21. The succeeding shingles are laid and nailed in this course in the same manner that the shingles were laid in the preceding course. It will thus be seen that although but two nails are driven through each shingle, every shingle is fastened at four places, namely at one of the lower corners, both of the upper corners, and adjacent the upper edge intermediate the upper corners. The other lower corner which is not nailed is held secure in flat position by the interlocking arrangement with the adjacent shingle. This construction allows each shingle to accommodate itself to the expansion and contraction of the roof boards without buckling or tearing.

To illustrate specifically an economical set of shingles, constructed according to my invention, the shingle A is twenty-two inches long between the lateral edges 14 and 15 and twelve inches high between the butt and head edges 16 and 17 with the right angle notch edges 12 and 13 measuring one and one-half and two and one-half inches inwardly from the butt and side edges respectively. The complementary shingle B is 17 inches between the lateral edges 24 and 25 and the same height between the head and butt edges 105 as the shingle A, with the tab edges extending outwardly from the lateral edges 24 and 25 a distance of two and one-half inches and upwardly from the butt edge a distance one and one-half inches. The shingles so constructed and dimensioned, may be laid so as to expose approximately four-fifths of the total height of the shingle in each course, with a two and one-half inch head and side lap. With the above described shingles it requires but ninety shingles per square 115 with a total of approximately 146 square feet of material per square, the finished structure having a side and head lap of two and one-half inches. Thus, a given area may be covered with a relatively small number of shingles and a minimum amount of material, the finished structure being entirely weatherproof and having a pleasing appearance.

I claim as my invention:

1. A roof covering comprising a plurality of 125 courses of shingles, one of said courses including a plurality of shingles having locking projections at their lower corners and laid in an alternate relationship with other shingles having recesses at each of their lower corners in interlocking engagement with said locking projections on adjacent shingles.

2. A roof covering comprising a plurality of courses of shingles, one of said courses including a plurality of unlike shingles laid alternately adjacent each other so that the tab extending at opposite edges of one shingle is overlapped by the shingles laid adjacent each of said opposite edges, said adjacent shingles each having their lower corners cut for interlocking engagement 140 with the tabs of the first named shingles.

3. A roofing or other surface covering comprising a plurality of courses of waterproof shingles, with one shingle having a recess at each of its lower corners and another shingle having tabs 145 at each of its lower corners, the shingles being laid side by side with the tabs of one shingle overlapped by the other shingle.

4. As an article of manufacture a set of roofing elements, one element of the set having a recess 150

at each of the lower corners thereof and another element of the set having a lateral extension at each of its lower corners.

5. As an article of manufacture a set of covering elements, one of the elements of the set comprising a body portion having a lateral projection or tab on each side of the body portion extending in opposite directions to each other from the lower end thereof, a second element of the set having a recess on each side of its body portion adjacent the lower end thereof, said recess being a counterpart of the tab on the first mentioned element.

6. A roofing or other surface covering comprising a plurality of courses of waterproof shingles, with alternate shingles of each course having a tab at each of its lower corners, overlapped by the adjacent shingles in the same course and in-

terlocking with recesses at the lower corners of said adjacent shingles.

7. A roof or other surface covering comprising a plurality of courses of sets of shingles laid in alternate adjacent, overlapping and interlocking relationship, the shingles of one set having locking tabs at the lower ends of its opposite sides which are the counterpart of recesses at the lower ends of the opposite sides of another of said sets of shingles.

8. A roofing or other surface covering comprising a plurality of courses of waterproof shingles, alternate shingles of each course having a notch at each of its lower corners to receive a locking projection on the lower corners of each of the adjacent shingles in the same course.
